UNITED STATES PATENT OFFICE.

ALEXANDER L. PATTERSON, OF BRONX, NEW YORK.

GOLF TEE.

Application filed May 10, 1926. Serial No. 107,997.

This invention relates to a golf tee, that is to an implement or article which is adapted to be thrust into the ground to serve as a support upon which a golf ball may be poised preparatory to striking the ball in the progress of the game.

An object of the present improvement is to provide a tee which will be simple and cheap to manufacture, which will be efficient in the performance of its several functions, and which will be not liable to be broken in use.

A more detailed object is to provide a tee so shaped that it may be readily thrust, as a peg, into the ground and will maintain itself efficiently in any position of use into which it is moved into the ground.

A further detailed object is to give to the tee a shape such that while it provides an efficient entering point or portion for piercing the ground it will also provide other portions for holding it against creeping upwardly from the ground and for holding it against unintentional movement or depression into the ground.

Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

In the accompanying drawings which are to be taken as a part of this specification, and in which I have shown merely a preferred form of embodiment of the invention:

Fig. 1 is a perspective view of a golf tee constructed in accordance with this invention and showing the same as it appears in use thrust into the ground, a golf ball being shown by dotted lines as resting upon the upper end of the tee.

Fig. 2 is a diagrammatic side elevational view of the tee shown in Fig. 1 and illustrating graphically the peculiar curvature and formation of the side walls of the tee.

Fig. 3 is a top plan view of the tee shown in Figs. 1 and 2, and

Fig. 4 is a view corresponding to the lower portion of Fig. 2 but illustrating a slight modification thereof.

Referring to the drawings for describing in detail the structure shown therein it will

be seen that the tee consists of what may be termed an upper end or head portion L and a lower end or stem portion G, the extreme lower end of the portion G being abruptly tapered or coned off as at 1 to enable said end to pierce the ground.

The upper end surface of the head portion L is suitably cupped at as 2, as is usual in tees of this type, for receiving and directly supporting golf ball H.

In use the lower end of the tee is thrust into the ground, as a small peg, a suitable extent of the upper or head portion of the tee being allowed to project above the ground to constitute a sort of temporary pedestal upon which the golf ball is poised for the strike-off.

Tees of this general type are old and well known accessories to the game of golf at this time but so far as I am aware such tees have not heretofore been constructed to efficiently hold themselves in their intended position within the ground and yet be in such form as to be unlikely to be broken in use.

I am aware that tees have been in use in which the stem portion has consisted of a long slender cylinder of uniform diameter with the head portion flaring abruptly at the upper end. While such tees are capable of being easily thrust into the ground in most cases yet they are very liable to breakage if the ground happens to be unusually hard or if a stone or pebble is encountered. They are also very liable to breakage, particularly at the sharp juncture of the head and stem portions, when the ball is struck.

I am also aware that tees have been suggested in which the head and stem portions constitute simply the upper and lower ends of a straight sided inverted cone, such for instance as illustrated in the patent to Pryde 1,522,544 issued January 13th, 1925. Such tees as these are indeed not liable to be broken in use, but the smooth uniformly tapering side walls offer serious objections, first, on account of the force required to be exerted in pressing them down into the earth. The ordinary soil of most golf courses is sufficiently hard and tough so that considerable pressure must be exerted to drive these pointed cones into it. And second, because of the fact that the continuously tapering walls of the cone produce an ever-present tendency causing the cones to "sponge", or creep, upwardly above the final

point of depression, and thus to such a looseness of fit within the earth as to render the use of the cones as tees unreliable.

I am also aware that tees have been suggested in which the walls of the stem portion have been slightly curved from a sharp lower end upwardly to the head portion, such for instance as illustrated in the patent to Daughady 1,538,173 issued May 19th, 1925, in which a tee of this shape is described as being formed of thin sheet metal. Liability to breakage in use is also reduced in this instance but the continuously upwardly flaring taper of the stem portion which is intended to enter the earth presents the same tendency to "sponge" or lift the tee upwardly above its point of final manual depression so that the tee becomes unstable and consequently a source of annoyance rather than an asset to its user.

The form of tee disclosed herein is designed to provide against likelihood of breakage in use and at the same time overcome the objections above pointed out with regard to the difficulty of driving the tee into the ground and the tendency to "sponge" upwardly after being driven.

The precise form of my improved tee for accomplishing these results is graphically illustrated in Fig. 2 wherein it will be seen that the entire extent of the side wall, or walls, as 3 of the tee, extending from the lower end cone-point 1 upwardly to the margin of the seat or pocket 2, is formed upon the arc of a single circle such as indicated by the lines 4-4 struck from a centre as 5 as indicated by the arrow 6. In the instance illustrated the horizontal plane of the centre 5, as indicated by the line 7, passes through the stem portion of the tee at a level slightly above the cone point 1 so that, while the portions as 8 of the side walls of the tee above this plane or line 7 taper increasingly upwardly and outwardly from said line, the portions as 9 of said side walls below said line 7 taper increasingly outwardly and downwardly from said line and result in a slightly enlarged foot 10 above the cone point 1 and below a region of minimum thickness at the level of line 7.

It will be apparent that by this means the driving down of the small cone point 1 will open up a cylindrical passage in the earth which will offer practically no resistance to the downward movement of the portions of the stem above the point until the flare of the upper walls 8 equals in diameter the extreme flare of the lower walls 9, that is approximately at the level of the line 11, said line being taken to represent the momentary level of the ground into which the tee is being forced.

At this stage of depression of the tee the outwardly flaring portion 8 of the walls begin to wedge into the cylindrical passage

formed by the point 1 and foot 10. The wedge action will be very gradual owing to the formation of said wall on the arc of a circle from point 5 and will continue with only slight increase until the tee has reached its final desired position of use, that is until the relative ground level approximately corresponds with the line 12.

The wedge action of that portion of the tee between lines 11 and 12 is found to be just sufficient in practical use to give an efficient steady grip of the mid or upper portion of the tee against the earth to prevent wabbling or looseness of the tee within the earth while at the same time being quite incapable of causing any upward "sponging," or creeping, of the tee away from its final driven position. The wedge action against the earth in most cases causes the underlying portions of the earth to be crowded against the stem of the tee between the point 1 and line 11, which further steadies the tee and also operates efficiently to counteract any slight tendency of the tee to "sponge" upwardly on account of the wedge action above line 11.

The foot 10 also will at all times constitute an anchor against unintentional movement of the tee.

This tee may be made of any desirable material, preferably wood, and the gradual change in diameter from the head portion to the stem portion will amply guard against likelihood of breakage between these portions. The real line of weakness is at the plane of line 7 which in use is so far beneath the level of the ground and at the same time so close to the lower end of the stem, that breakage is practically precluded in ordinary use of the device.

In some instances it may be found desirable to make the lower end portion of the tee, that is the portion below the plane of line 7, with parallel walls, thus omitting the slight increase in diameter constituting the foot 10 above mentioned. In this case the portion of the tee below the line 7 and above the point 1 would be of unchanging diameter as suggested by the modification Fig. 4. Such a structure as this will enter the earth with slightly greater ease than where the relatively larger foot 10 is present, and owing to the extremely slight taper, and consequent wedge action of the part of the tee between lines 7 and 11 the wedge action, and the consequent tendency to "sponge" upwardly will be negligible and quite fully counteracted by the grip of the parallel portion upon the deeper earth.

As many changes could be made in this construction without departing from the scope of the invention as defined in the following claims, it is intended that all matter contained in the above description or shown in the accompanying drawings, shall be in-

terpreted as illustrative only and not in a limiting sense.

Having thus described my invention, what I claim as new and desire to secure by Letters Patent is:—

1. A golf tee comprising an elongated body pointed at its lower end and having a relatively enlarged ball receiving seat at its upper end, said tee being intended to be thrust partly into the ground, and the side walls of the tee being tapered downwardly and continuously concavely curved on the arc of a circle from adjacent the relatively large upper end downwardly along that part which is intended to stand above the surface of the ground and continuing along that part which is intended to stand below the surface of the ground and to adjacent said pointed end.
2. A golf tee comprising an elongated body pointed at its lower end and having a relatively enlarged ball receiving seat at its upper end, said tee being intended to be thrust partly into the ground, and the side walls of the tee being tapered downwardly and continuously concavely curved on the arc of a circle from adjacent the relatively large upper end downwardly along that part which is intended to stand below the surface of the ground and to adjacent said pointed end, the centre of the arc defining said side walls being in a horizontal plane spaced vertically above the lower end of the tee.
3. A golf tee comprising an elongated body having head and stem portions, the head portion having a ball seat concentrically of its upper surface, the stem portion having a conical entering point at its lower end and being intended to be thrust at least partly into the ground, the side walls of the tee flaring upwardly and outwardly along the stem portion and merging gradually into the head portion to thereby provide gradual enlargement of the stem portion in its region which is intended to stand adjacent the surface of the ground adapted to indeterminately oppose downward movement of the tee into the ground, the stem portion in its region below the mentioned region being of a relatively less diameter, and the stem portion in its region appreciable below the last mentioned region and above the conical entering point being of a diameter at least as great as the diameter of the second mentioned region, all for the purpose set forth.
4. A golf tee comprising an elongated body having head and stem portions, the head portion having a ball seat concentrically of its upper surface, the stem portion being intended to be thrust at least partly into the ground, the side walls of the tee flaring upwardly and outwardly along the stem portion and merging gradually into the head portion to thereby provide gradual enlargement of the stem portion in its region which is intended to stand adjacent the surface of the ground adapted to indeterminately oppose downward movement of the tee into the ground, the part of the stem portion which is intended to stand beneath the surface of the ground being annular and being of relatively great diameter in its regions intended to stand deep within the ground and adjacent the surface of the ground and being of relatively less diameter in its region intermediate the two mentioned regions.

In testimony whereof I affix my signature.
ALEXANDER L. PATTERSON.
